LAUNDRY MACHINE UTILIZING A WOBBLE-
TYPE AGITATOR

Edward J. Doyle, Hatboro, Pa., assignor to Philco Corporation, Philadelphia, Pa., a corporation of Delaware
Filed Feb. 21, 1962, Ser. No. 174,809
20 Claims. (Cl. 68—23)

This invention relates to laundry machines, and more particularly to laundry machines utilizing wobble-type agitators.

In laundry machines generally, it is the practice to achieve effective washing by imparting vigorous movements to the clothes being laundered. In wobble-type laundry machines, the washing action is accomplished by freely journaling an agitator of suitable configuration on an obliquely disposed member, such as an inclined portion of a rotatable drive shaft, the agitator being prevented from rotating with respect to the tub by suitable restraining means. Continuous unidirectional rotation of the drive shaft, acting through the inclined shaft portion, imparts a nonrotational undulatory or wobbling motion to the agitator, producing circulation of the washing fluid and causing articles being washed to be brought into intimate contact with the turbulent streams of water generated by movement of the agitator.

The problem of "clothes smothering" in wobble-type machines has been met by provision of a column extending upwardly from the center of the agitator, which column prevents clothes from covering the agitator assembly by virtue of its presence in this region. Apparatus of this type is disclosed and claimed in U.S. Patent No. 2,902,851, issued to George C. Fields on September 8, 1959, and assigned to the assignee of this invention. In the reference patent, mechanism is provided whereby motion of the column is distinct from that of the agitator assembly in order to set up currents which act to provide more efficient washing of the clothes while preventing smothering. In apparatus of this type linkage means is provided to bring about the above described movements, which means requires its own flexible seals.

It is an objective of the present invention to provide an improved combination of a stationary column and wobble-type agitator apparatus through which the number of linkages and linkage seals is reduced, and which combination achieves optimum washing action.

In achievement of the foregoing and other objectives, the invention contemplates provision of a wobble-plate agitator supported by a spider bracket structure affixed to suitable bearing means mounted upon an inclined shaft extending into the tub and spin basket of a washing machine. A vertically extending column is supported concentrically with the tub and basket by bracket means affixed to the basket and including leg portions that interdigitate with the agitator support bracket structure. The construction and arrangement is such that the agitator support bracket undulates within the spaces between the leg portions of the column support bracket. The agitator assembly is, in one embodiment of the invention, suitably apertured whereby turbulent streams of wash-fluid are created by a pumping action which directs such streams downwardly through the agitator and outwardly from the bottom and through the space between the agitator and the basket.

For a better understanding of the foregoing as well as other objects and features of the invention, reference may be had to the following description taken in light of the accompanying drawing, in which:

FIGURE 1 is a perspective showing of a laundry machine embodying the invention;

FIGURE 2 is an elevational view of the machine illus-

trated in FIGURE 1, partly in section and with parts broken away, and illustrating one embodiment of the invention;

FIGURE 3 is an elevational view of the embodiment shown in FIGURE 2, partly in section and with parts removed;

FIGURE 4 is a view similar to FIGURE 2, looking in the general direction of arrows 4—4 applied to FIGURE 5, and illustrating a second embodiment of the invention; and

FIGURE 5 is a plan view of the embodiment of the invention illustrated in FIGURE 4, and with parts removed.

With more particular reference to the drawings, and first to FIGURE 1, the invention is embodied in a washing machine 10 of the type including a cabinet 11 having a top wall 12 provided with an access opening 13, and a door 14 hingedly mounted over the opening. Control means for the machine comprise control elements, see, for example 15 and 16, mounted upon a panel 17.

In the embodiment of the invention illustrated in FIGURES 2 and 3, an upwardly presented tub 21 is housed within the cabinet. Tub 21 is supported upon a tubular column 22 that is resiliently mounted upon suitable base means (not shown) forming part of the cabinet 11. There are also housed within the cabinet suitable motor and transmission means, such for example as is disclosed and claimed in the copending disclosure of Joseph Pelensky, filed December 26, 1961, bearing Serial No. 161,962, and assigned to the assignee of the present invention. The relationship of the motor and transmission means to the apparatus of the present invention, while not necessary to an understanding of the latter, will be discussed briefly later in this description.

An upwardly presented rotatable clothes container means or basket 23 is nested within tub 21 and supported upon hub means 24 journalled within bearing means 25 provided in the bottom of stationary tub 21, in the region of the upper end of column 22. A hollow shaft 26 extends downwardly from hub means 24, concentrically as respects column 22, and is connected to the output drive of the transmission which provides high speed spin of basket 23. A solid shaft 27 is disposed concentrically within the hollow shaft 26. Shaft 27 is journalled by bearings 28 and 29 for rotation within hub means 24 and its extension 26, and is adapted to be rotated by the output drive of the transmission which provides for operation of agitator 31. Agitator 31 will be described in detail in what follows, and first as respects the embodiment of the invention illustrated in FIGURES 2 and 3.

The upper end of shaft 27 includes an inclined portion 32, and an annular base 33 for agitator 31 is journalled to inclined shaft portion 32 by bearing means 34. Agitator base 33 is restrained from rotating relative to basket 23 by a flexible sleeve 35 that extends from clamped sealing engagement with base 33 into clamped sealing engagement with basket hub 24. Hub 24 is sealed to tub 21 by means of cylindrically formed seal 36 and flexible and resilient face seal 37 which seals, with slidably abutting engagement, against a ring 41 disposed concentrically with and in the bottom of tub 21. Ring seals are provided as seen at 42 between base 33 and shaft portion 32, and at 43 between hub 24 and shaft portion 32. A plate 44 is clamped to agitator base 33 and closes the end of this element. Plate 44 is clamped to base 33 by base portions 46 of the spider element 45, which portions 46 are forcibly urged against base 33 by studs 47 through the intercession of the plate 44 and the gaskets as shown.

Spider 45 includes legs 53 that extend with clearance through generally vertically extending slots 55 provided in a generally conical member 54 mounted at its base to

basket 23, in concentric relation thereto. At the vertex of member 54 is a vertically extending rod 56 upon which is mounted a generally tapered column 57 including a downwardly flared portion 58 at its lower end.

Agitator 31 further includes a ring 61 provided with a flat portion 62 which is supported upon legs 53 of spider 45, and a generally downwardly presented undulatory portion 63. An annular flexible and resilient flipper or vane 64 is clamped against undulatory portion 63 of ring 61 by a ring 65 which includes a similar undulatory portion 66, and vane 64 assumes the undular shapes thereof. Ring 65 also comprises a flattened upper portion 67 which includes a central opening 68 through which column 56 extends with substantial clearance. Portion 67 of ring 65 is disposed and adapted, upon undulatory movements of the agitator, to move into and out of the space enclosed by downwardly flaring portion 58 of column 57, whereby to effect at fluid pumping action.

The central portion of basket 23, in the region of hub means 24 beneath conical member 54, includes a depression 71 which has a plurality of apertures 72. Apertures 72 together with slots 55 in member 54 provide fluid flow communication between the interior of basket 23 and tub 21. The fluid flow path provided by apertures 72 and slots 55 is so positioned relative to the agitator as to accommodate flow of turbulent streams of wash fluid downwardly through the opening 63, slots 55, apertures 72, and into tub 21. From tub 21, the fluid flows upwardly through apertures 73 provided in the bottom of basket 23, following which the fluid is drawn between column flare 58 and ring 65 for subsequent turbulent flow as described previously. Pumping action is achieved by the agitator, to create this turbulent flow, through the alternate "squeezing" and releasing of the fluid between column flare 58 and agitator ring 55 concurrently with alternate releasing and "squeezing" of the fluid between agitator vane 64 and ring 61, and member 54 and basket depression 71.

In achievement of the above described washing action basket 23 is held stationary by suitable brake means (not shown) while agitator shaft 27 is rotated by the drive motor. Such mechanism, as noted earlier in this description, may be made in accordance with the referenced Pelensky disclosure. As shaft 27 is rotated, the inclined portion 32 moves orbitally with both translational and rotational movements. In rotating, the inclined shaft portion has relative movement with respect to agitator base 33, through bearing 34. The agitator 31, however, is prevented from rotating relative to basket 23 by flexible sleeve 35, such that movements of the agitator are undulatory, and legs 53 of spider 45 move up-and-down within slots 55 provided in conical member 54, as clearly appears in FIGURE 3, and in non-interfering relation with respect to leg portions of the conical member comprising the solid sections between the slots 55.

A modified embodiment of the invention is illustrated in FIGURES 4 and 5 in a machine comprising a non-rotatable tub 80 supported upon a resiliently mounted, vertically extending tubular column 81. A rotatable container means or basket 82 (shown fragmentarily) is supported upon hub means 83 which, as in the embodiment illustrated in FIGURES 2 and 3, includes a hollow shaft 85 extending downwardly therefrom concentrically with column 81. Hub means 83 is journaled for rotation within tub 80 by bearing means 84 disposed between hub extension 85 and column 81. A solid shaft 86 is concentric with hollow shaft 85, and is journaled by bearing 87 within hub means 83 for rotation relative to the hub means and its shaft extension 85.

The upper end of shaft 86 includes an inclined portion 91 affixed to the former by a pin 92. A generally disk shaped agitator base 93 is journaled to inclined shaft portion 91 by a bearing 94, and agitator base 93 is restrained from rotating relative to basket 82 in part by a flexible sleeve 95 that is clamped in fluid-tight relation to the base

93 and hub 83 of the basket. Hub 83 is sealed to the tub by means of face seal 96.

A cylindrical member 97 of the agitator includes a lower outwardly presented flange portion 101 and an upper, inwardly presented undulated flange portion 102. Member 97 is mounted to base 93 by means of bolts (not shown) that clamp flange portion 101 to a confronting annular flange portion 103 of agitator base 93. The peripheral portions of flanges 101 and 103 are so configured and adapted to clamp a bead portion of an annular seal 108 that is clamped also along its outer rim to the bottom of basket 82, along the edge of a depressed portion 104 of the latter disposed below the agitator.

An annular vane 105 is clamped between undulatory flange 102 and a similarly undulatory plate 106, by bolts as shown. Agitator vane construction of this general type is disclosed in the hereinbefore mentioned U.S. Patent No. 2,902,851, and reference may had thereto for a full showing if desired. The vane 105 includes an upwardly extending bellows portion 107 that is clamped in fluid-tight relation to a suitably formed portions of a central column designated generally by the numeral 111. Seal 108, bellows portion 107 and sleeve 95 cooperate to restrain the agitator from rotating relative to basket 82.

According to the invention, the agitator base 93 has three slotted openings 112 through which extend the rod-like legs 113 of column 111, in interdigitating or interposed non-interfering relation to leg portions of the slotted base. Legs 113 of the column serve as a rigid support for the same and are mounted upon hub means 83 of basket 82. Legs 113 include horizontally extending portions that converge centrally as respects the agitator and support an upwardly extending rod 114. Column 111 further includes a vertically extending tapered member 115 provided with a lower, downwardly flared portion 116 that overlies undulated plate 106 and is mounted to a clamping plate 117 which clamps bellows portion 107 of flipper 105 to flared portion 116 of member 115. Plate 117 is, in turn, fixedly mounted upon rod 114 by a screw threadedly received within the latter.

In the achievement of the washing action, basket 82 is held stationary and agitator shaft 86 is rotated by the drive motor. Rotation of shaft 86 causes agitator base 93 and structure affixed thereto to undulate in the same manner as the agitator in FIGURES 2 and 3. The agitator undulates freely relative to the column 111, the agitator base moving vertically as respects the legs 113 which extend with clearance through openings 112 provided in the former. As a result of this movement, fluid is alternately squeezed and released between vane 105 and its bellows portion 107, and further is impelled alternately upwardly and downwardly by vane 105.

From the foregoing description it will be appreciated that the invention achieves optimum washing action, by virtue of the turbulent streams of wash fluid impelled by the agitator vanes. These vanes cooperate with the fixed support column to achieve improved washing action, while the latter element prevents smothering of the agitator action by preventing fabrics being washed from settling atop the agitator. Moreover, by fixedly mounting the column upon for example tripod means as illustrated, there is achieved a desirable relative movement between the same and the agitator which enhances the washing action, yet requires no mechanical linkage between the agitator and column.

While a pair of preferred embodiments of the invention has been illustrated and described, it will be understood that the invention is susceptible of other modifications within the scope of the appended claims.

I claim:

1. In a laundry machine, the combination comprising: basket means within which may be disposed clothes to be washed; bracket means disposed within said basket means including a central portion concentric with the axis of said basket means, and leg portions having base

means mounting the bracket means upon said basket means; column means supported by said bracket means and extending coaxially with said central portion of said bracket means; and wobble-plate agitator means within said basket means, including radially extending portions disposed in interdigitating relation with said leg portions of said bracket means, and vane means supported by said radially extending portions.

2. The combination according to claim 1, and further characterized in that said bracket means comprises a hollow member and said leg portions are defined by apertured wall portions of said member through the apertures of which said radially extending portions extend, said member having its base portion affixed to said basket means.

3. The combination according to claim 1, and further characterized in that said agitator means includes a generally disk shaped base member having openings through which said leg portions of said bracket means extend.

4. The combination according to claim 1, and further characterized by: said vane means comprising an undulatory flexible and resilient annular member; and by the inclusion of a pair of plates clamping said member and supported upon said radially extending portions, one of said clamping plates being disposed above the other and comprising a ring portion including a surface disposed within angularity as respects, and in overlying relation to, said plate, said plate and ring portion encircling said column means with clearance; and by said column including a downwardly flaring portion spaced from and substantially overlying said ring portion, the construction and arrangement being such that upon undulating movement of the agitator means, wash fluid within said basket is caused to be pumped, by the cooperative action of said ring and said column means flaring portion, through the central opening of said agitator means and through spaces between elements of said leg portions of said bracket means.

5. In a laundry machine, the combination comprising: tub means; perforate basket means mounted for rotation about its axis within said tub means; bracket means disposed within said basket and including leg portions mounted upon said basket means and further including a central portion concentric with said axis; column means extending coaxially with said central portion of said bracket means; and wobble-plate agitator means within said basket means, including radially extending arms disposed in interdigitating relation as respects said leg portions of said bracket means, and vane means supported by said arms.

6. The combination according to claim 5 and further characterized in that said bracket means comprises a hollow member and said leg portions are defined by apertured wall portions of said member through the apertures of which said support arms extend, said member having a base portion affixed to said basket means.

7. The combination according to claim 5, and further characterized in that said agitator means includes a generally disk-shaped base member having openings through which said leg portions of said bracket means extend.

8. The combination according to claim 5 and further characterized by: said vane means comprising an undulatory flexible and resilient annular member; by the inclusion of a pair of plates clamping said member and supported upon said radially extending portions, one of said clamping plates being disposed above the other and comprising a ring portion including a surface disposed with angularity as respects and in overlying relation to, said plate, said plate and ring portion encircling said column with clearance; and by said column means including a downwardly flaring portion spaced from and substantially overlying said ring, the construction and arrangement being such that upon undulating movement of said agitator means, wash fluid within said basket is caused to be pumped, by the cooperative action of said ring and said column means.

column means flaring portion, through the central opening of said agitator means and through spaces between leg portions of said bracket means.

9. In a laundry machine, the combination comprising: tub means; perforate basket means mounted for rotation about its axis within said tub means; tripod means mounted within said basket means and including a central portion concentric with said axis; a column extending coaxially with said central portion of said tripod means; and wobble-plate agitator means within said basket means, including radially extending arms disposed in interdigitating relation as respects said tripod means, and vane means supported by said arms.

10. The combination according to claim 9, and further characterized in that said tripod means comprises a generally conical member including apertures through which said support arms extend, said conical member having a base portion affixed to said bracket means.

11. The combination according to claim 9, and characterized in that said vane means comprises an undulatory flexible and resilient annular member, and further characterized by the inclusion of plates clamping said member and supported upon said arms.

12. The combination according to claim 11 and further characterized by: one of said clamping plates being disposed above the other and comprising a ring portion including a surface disposed with angularity as respects, and in overlying relation to, said plate, said plates and ring portion encircling said column with clearance; and by said column including a downwardly flaring portion spaced from and substantially overlying said ring, the construction and arrangement being such that upon undulating movement of said agitator means, wash fluid within said basket means is caused to be pumped, by the cooperative action of said ring and said column flaring portion, downwardly through the central opening of said agitator means and through spaces between elements of said tripod means.

13. A combination according to claim 9, and further characterized in that said tripod means comprises a plurality of legs supported upon said basket means, and said agitator means comprises a generally disk shaped base member including openings through which said legs of said tripod means extend.

14. In a laundry machine, the combination comprising: tub means; perforate basket means mounted for coaxial rotation within said tub means and including a depressed central portion having apertures therein; tripod means mounted within said depressed portion of said basket means and including a central portion concentric with the basket means; column means extending upwardly from said central portion of said tripod means, the latter comprising a generally downwardly flaring conical member having apertures therein; and wobble plate agitator means disposed within said basket means, said agitator means including radially presented arms extending through said apertures in said conical member, said agitator further including an undulatory flexible annular member and a pair of plates clamping said member and supported upon said arms, one of said clamping plates being disposed above the other and including a ring portion having a surface disposed with angularity as respects and overlying relation to said one plate, said plates and ring portion encircling said column means with clearance, and said column means including a downwardly flaring portion spaced from and substantially overlying said ring portion, the construction and arrangement being such that upon undulating movement of said agitator means, wash fluid within said basket means is caused to be pumped, through the cooperative action of said ring and said column means and the cooperative action of said resilient member and said conical member, downwardly through the central opening of said agitator means and through openings in said conical member thence outwardly through apertures provided in said depressed portion of said basket means.

15. In a laundry machine, the combination comprising:

container means within which clothes to be washed may be disposed; bracket means disposed within said container means and including leg portions provided with base means for mounting said bracket means within said container means; wobble-plate agitator means within said container means, including radially presented portions interposed in noninterfering relation with leg portions of said bracket means, and vane means supported by said radially presented portions; and column means carried by said bracket means and extending therefrom upwardly within said container means.

16. The combination according to claim 15, and further characterized in that said bracket means comprises a hollow member, said leg portions are defined by apertured wall portions thereof, and said radially presented portions extend through such apertures.

17. The combination according to claim 15, and further characterized in that said agitator means includes a generally disk shaped base member having openings through which said leg portions of said bracket means extend.

18. The combination according to claim 15, and further characterized in that said bracket means comprises a generally conical member having apertures through which said radially presented portions of said agitator means extend, the base portion of said conical member defining said base means and affixed to said container means.

19. The combination according to claim 15 and char-

acterized in that said leg portions are defined by individual rod-like members extending upwardly from pads defining said base means.

20. The combination according to claim 15 and further characterized by: said vane means comprising an undulatory flexible and resilient annular member, and by the inclusion of a pair of plates clamping said member and supported upon said radially presented portions, one of said clamping plates being disposed above the other and comprising a ring portion including a surface disposed with angularity as respects, and in overlying relation to, said plate, said plate and ring portion encircling said column means with clearance, and by said column means including a downwardly flaring portion spaced from and substantially overlying said ring portion, the construction and arrangement being such that upon undulating movement of said agitator means, wash fluid within said container means is caused to be pumped, by the cooperative action of said ring portion and said column flaring portion, through the central opening of said agitator means and through spaces between leg portions of said bracket means.
